US00D635935S

(12) **United States Design Patent**
Donowho

(10) **Patent No.:** **US D635,935 S**
(b4) **Date of Patent:** **** Apr. 12, 2011**

(54) **COVER FOR CABLE MANAGEMENT RACEWAY**

6,107,576 A 8/2000 Morton et al.
6,307,997 B1 10/2001 Walters et al.
6,437,243 B1 8/2002 VanderVelde et al.

(75) Inventor: **D. Brian Donowho**, Austin, TX (US)

CLAIM

The ornamental design for a cover for cable management raceway, as shown.

DESCRIPTION

FIG. 1 is an isometric view of a cover for cable management raceway, depicted in a horizontal orientation, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.
